UNITED STATES PATENT OFFICE.

FINIS W. CREAGER AND ORA L. WILSON, OF CECILIA, KENTUCKY.

SLIDING-DOOR FASTENER.

1,190,519.

Specification of Letters Patent. Patented July 11, 1916.

Application filed March 31, 1916. Serial No. 87,976.

To all whom it may concern:

Be it known that we, FINIS W. CREAGER and ORA L. WILSON, citizens of the United States, residing at Cecilia, in the county of 5 Hardin and State of Kentucky, have invented certain new and useful Improvements in Sliding-Door Fasteners, of which the following is a specification.

The present invention relates to improvements in locks and has particular reference to a self-acting lock adapted for use in connection with sliding or reciprocatory doors, such as car doors.

An important object of the invention is to 15 provide means whereby a car door which has been left partly or wholly open, upon moving to the closed position, due to bumps or jars upon the car, will be securely locked in such closed position whereby the door is 20 prevented from being subjected to unnecessary strains.

A further object of the invention is to 25 provide a lock of the above mentioned character, which is simple in construction, inexpensive to manufacture, strong, and durable.

Other objects and advantages of the invention will be apparent during the course of the following description.

30 In the accompanying drawings forming a part of this specification and in which like numerals are employed to designate like parts throughout the same, Figure 1 is a side elevation of a lock embodying our invention, 35 showing the same in use, Fig. 2 is a longitudinal sectional view taken on line 2—2 of Fig. 1, Fig. 3 is a similar view taken on line 3—3 of Fig. 1, Fig. 4 is a horizontal sectional view taken on line 4—4 of Fig. 1, and, 40 Fig. 5 is a similar view taken on line 5—5 of Fig. 1.

In the drawings, wherein for the purpose of illustration is shown a preferred embodiment of our invention, the numeral 10 designates the body of a car having a sliding or reciprocatory door 11, supported by wheels 12, traveling upon a track 13. Secured to the side of the body 10 adjacent one side of the door opening is a door jamb 14, 50 having a recess 15 formed therein. Secured to the inner edge of the beam 14 is a protecting plate 16, as shown. This protecting plate, as more clearly shown in Fig. 4, is provided with an opening 17, for a purpose 55 to be described. Mounted within the recess 15 is a control member or lever 18, provided

at its upper end with apertured knuckles 19, receiving a pivot element or bolt 20, secured to the beam 14. It is thus apparent that the control member 18 is pivoted to 60 swing in a vertical plane. Arranged within the recess 15 inwardly of the control member 18 is a bolt-spring or bar 21, the lower end of which is attached to the beam 14 by means of a bolt 22 or the like. The upper 65 end of the bolt-spring or bar 21 fits loosely within a U-shaped member or staple 23 rigidly attached to the upper portion of the control member 18 near and spaced beneath its pivot 20. The bolt spring or 70 bar 21 is normally straight and serves to normally retain the control member 18 in the inner vertical position.

Means are provided to lock the control member 18 in the inner or vertical position, 75 comprising a reciprocatory latch bolt 24, carried by the control member 18 and operating in a longitudinal recess 25 thereof. This latch bolt has its lower end beveled and projects into a recess 26 and is adapted 80 for detachable engagement with a staple or apertured member 27 held stationary to the door jamb 14. The latch bolt 24 is moved downwardly by a compressible coil spring 28 and may be moved upwardly by a lateral 85 extension or finger hold 29, sliding between apertured lugs or ears 30 formed integral with the control member 18. A key 31 is inserted through the apertures of the member 29 and the lugs 30 and has a head 32 90 at one end and an aperture 33 at the other end for receiving a seal 34. When the key 31 is in place it is obvious that the control member 18 is locked against upward movement. 95

Secured to the door 11 is a door bolt 35, having a hooked head 36, adapted to engage behind the bolt-spring 21. The control member 18 has a recess 37 adjacent the door bolt 35, which will permit of the yielding action of the bolt-spring 21, and the passage of the head of the door bolt, the bolt-spring returning to its normal position and locking the door-bolt against movement. 100

In operation, when the control member 18 is in the closed position, and the door 11 is open, when the door is moved to the inner closed position the door-bolt 35 contacts with the bolt spring 21 moving it laterally and finally having locking engagement therewith. The door-bolt 35 cannot be withdrawn without swinging the control mem- 105 110

ber 18 to the outer position, to effect a disengagement between the hooked end of the door-bolt 36 and the bolt-spring or bar 21. It is apparent that the bolt-spring 21 serves 5 a double function, to wit, as automatic means to return the control member to the inner vertical position, and to lock the door-bolt 35 against movement.

It is to be understood that the form of 10 our invention herewith shown and described is to be taken as a preferred example of the same, and that various changes in the shape, size, and arrangement of parts may be resorted to without departing from the spirit 15 of the invention or the scope of the subjoined claims.

Having thus described our invention, we claim:

1. In a lock of the character described, 20 the combination with a support, of a door-bolt adapted for movement with relation to the support, a bolt-spring connected with the support and adapted to engage with the door-bolt and to move laterally with relation thereto to release it, a control member pivotally connected with the support and having connection with the bolt-spring to move it laterally, and means to hold the control member in the closed position.
2. In a lock of the character described, 30 the combination with a support, of a door-bolt adapted for movement with relation thereto, a bolt-spring connected with the support to engage with the door-bolt and to be moved laterally to disengage the door-bolt, a control member pivotally connected with the support and having connection with the bolt-spring, a stationary member

secured to the support, and a latch bolt carried by the control member to engage 40 with the stationary member.

3. In a lock of the character described, the combination with a vertical support, of a horizontal reciprocatory door-bolt movable with relation thereto, an upstanding 45 bolt-spring having its lower end secured to the support and its upper end adapted to move laterally, a vertically swinging control member having its upper end pivotally connected with the support and connected 50 with the bolt-spring near its pivot, a stationary apertured member secured to the support near the lower end of the control member, a spring pressed latch bolt carried by the control member to engage the apertured 55 stationary member, and means to lock the latch bolt against movement.

4. In a lock of the character described, 60 the combination with a support, of a door-bolt adapted for movement with relation to the support, a co-acting bar connected with the support and adapted to engage with the door bolt and to be moved laterally with relation thereto to release it, and a gravity operated control member pivotally connected with the support and having connection 65 with the co-acting bar to move it laterally.

In testimony whereof we affix our signatures in presence of two witnesses.

FINIS W. CREAGER.
ORA L. WILSON.
